UNITED STATES PATENT OFFICE.

GEORGE B. MARX, OF NEW YORK, N. Y.

COAL-WAGON.

SPECIFICATION forming part of Letters Patent No. 558,590, dated April 21, 1896.

Application filed January 6, 1896. Serial No. 574,441. (No model.)

To all whom it may concern:

Be it known that I, GEORGE B. MARX, a citizen of the United States, residing in the city, county, and State of New York, have invented 5 certain new and useful Improvements in Coal-Wagons, &c., of which the following is a specification, reference being had to the accompanying drawings, forming a part hereof.

Devices of great variety have been suggested hitherto and have been used for the purpose of facilitating the unloading of coal or other material from trucks or wagons and from railway-cars. In some cases the body of the wagon is arranged to be elevated and tilted; but this construction is not available for railway-cars or even for the large and heavy trucks which are now commonly used. In other cases the bottom of the body is inclined toward the point of delivery sufficiently 15 to insure a free movement of the coal or other material when unloading, and the delivery-chute is arranged sometimes at the end of the body, but more often and preferably at a central point, so that it does not become necessary to back the wagon or truck up to the point where the coal or other material is to be delivered, but permits it to be drawn up alongside the curb or wall. In this case it becomes desirable to provide for the delivery 20 of the coal or other material from either side of the wagon or truck; and it is in improved means for this purpose and for controlling the delivery of the coal or other material that my present invention consists.

35 The novel features of construction will be fully described hereinafter with reference to the accompanying drawings, in which—

Figure 1 is a side elevation of a coal truck or wagon to which my improvements are applied. Fig. 2 is a section on the line $x-x$ of Fig. 1, with the parts in position for the delivery of the coal at one side of the truck or wagon. Fig. 3 is a similar view on the line $y-y$ of Fig. 1, with the parts in like position. 40 Fig. 4 is a detail view of a portion of the delivery devices in section on the plane indicated by the line $z-z$ of Fig. 5. Fig. 5 is a detail sectional view of the same parts in a plane at right angles to that of Fig. 4, and Fig. 6 45 is a plan view of one end of the delivery pan or trough and its swinging door.

The body A of the wagon or truck is con-

structed in any suitable manner, with the bottom inclined from the ends toward the middle portion to facilitate the movement of the coal toward the transverse opening a, and it is supported upon the running-gear in any suitable manner. At each side of the opening a is secured a cheek-piece B, which depends a short distance below the bottom of the body, 55 each cheek-piece being preferably cut away at the lower corner, as at b. Between the cheek-pieces is disposed a tilting pan or trough C, which has at each end short oppositely-projecting lugs or pins c c, which enter corresponding slots d d in the normally horizontal arms or wings d' d', formed upon or secured to a swinging plate or door D. The latter is hinged to the body of the wagon, as at d², and is normally held with the arms or wings d' 60 horizontal, thereby supporting the pan or trough C in a horizontal position. Each plate D, with its arms or wings d' d', is, however, adapted to swing into a position represented at the left in Figs. 2 and 3, thereby permitting the corresponding end of the tilting pan or trough C to drop down and permit movement of the coal outward in a corresponding direction, the other end of the pan or trough C being held in its elevated position by the 65 engagement of its pins c c in the slots d d of the other pair of wings or arms d' d', which are still held in their horizontal position.

Each plate D is provided with an aperture d³ to receive a tongue c', which projects from 70 the corresponding end of the pan or trough C. The tongue c' also has an eye c² to receive a pin c³, which prevents the accidental release of the pan or trough C.

It is obvious that the chief function of the 75 plates or doors D D, with their slotted arms or wings d' d', is to permit the necessary tilting of the pan or trough C, and to permit it to be sustained in a horizontal position, or with one end or the other dropped. To control the 80 movement of the coal and also to enable either end of the pan or trough C to be raised when required, as well as to hold it up when raised, I provide at each end of the opening a a vertically-sliding gate E, which is formed with a hook e to engage the corresponding end of the pan C. Each gate E preferably has secured thereto a rack F, which slides in a suitable 85 guide, secured to the side of the body A, and

is engaged by a pinion f' , fast on a short shaft f^2 . The latter is supported in a suitable bearing in the side of the wagon-body A and is formed, as at f^3 , for engagement by a suitable crank, by which the rotation of the shaft may be effected. The shaft is also preferably provided with a ratchet-wheel f^4 , which is engaged by a hold-pawl f^5 to prevent backward rotation of the shaft. The hook e on the gate 10 E is preferably arranged to project through a hole c^4 in the bottom of the pan or trough C and to engage a bolt G, which is supported in suitable brackets g to slide longitudinally, is pressed forward by a spring g' , and is provided 15 with a suitable handle g^2 , by which it may be released from the hook e when required. The hook e and the bolt G are suitably beveled, so that the engagement of the two may be effected automatically.

20 In suitable hangers a^2 , which are secured to the bottom of the wagon-body, are supported the usual telescoping chutes H H', the outer chute H preferably being provided with hooked fingers h at each end, which, as the 25 chute is drawn out, are adapted to engage the pins c of the depressed end of the pan or trough C, as shown clearly in Fig. 2, to prevent the drawing out of the chute too far. The pin c^3 , before referred to, is made long 30 enough to stand across the ends of the chutes H H' as they are in place in the hangers a^2 and prevent their accidental displacement.

Before the wagon is loaded the pan C is sustained in a horizontal position by the engagement of the vertically-movable gates E E with the bolts G G by means of the hooks e e , the gates themselves being held in position by the engagement of the hold-paws with the ratchet-wheels on the shafts which carry the 35 pinions f' f' , the gates E E at the same time preventing the outward movement of the coal against the swinging doors or plates D D. When the wagon has been loaded and it is desired to deliver coal at one side or the other, 40 the pin c^3 at the proper side is pulled out of the eye c^2 of the tongue c' , which projects from the pan C through the hole in the corresponding plate or door D, thereby permitting the 45 said door or plate D to be swung outwardly. The bolt G may then be disengaged from the 50 hook e , thereby permitting the end of the pan C to drop, which movement of itself will cause the door D to swing into the position shown at the left in Figs. 2 and 3, or the end of the 55 pan may be lowered more gently by lowering the gate E without disengaging the bolt G therefrom until the end of the pan has reached its lowest position. Finally, the gate E is drawn up to the desired extent to permit the 60 movement of the coal outward through the pan C.

If it is desired at any time to stop the movement of the coal, the gate E is lowered until the hook e engages the bolt G, at the same 65 time stopping the movement of the coal. The gate is then raised partly, lifting with it the end of the pan or trough C until it is once more

in a horizontal position, and at the same time the plate D swings back to its normal position, the tongue c' of the pan or trough C entering the hole d^3 , and the pin c^3 being replaced the pan is thereby secured in its horizontal position.

It will be understood that while I have herein described my improvements as adapted 75 specially for use with coal-wagons, nevertheless I do not intend thereby to restrict the invention to any particular use, inasmuch as the improvements are obviously applicable to coal-cars and to wagons, trucks, or cars 80 for transporting and delivering material other than coal. It is also to be understood that I do not intend to limit my invention to the precise construction and arrangement of parts which are herein shown and described. 85

What I claim, and desire to secure by Letters Patent, is—

1. The combination with a body of a coal or other wagon having a delivery-aperture in its bottom, of a delivery-pan arranged below 90 said aperture and extending from side to side of said body, slotted arms connected to said body and engaging said pan at the ends thereof, whereby either end is permitted to drop to a limited distance, and vertically-movable gates carried by said body and adapted to be lowered and raised to prevent and permit the movement of coal outward through said pan, substantially as shown and described.

100

2. In a coal or other wagon, the combination with a body having a delivery-aperture in its bottom, of a delivery-pan arranged below said aperture and extending from side to side of said body, a plate or door hinged to 105 said body at each side thereof and having slotted arms to engage the corresponding end of said pan, whereby either end is permitted to drop to a limited distance, vertically-movable gates carried by said body and adapted 110 to be lowered and raised to prevent and permit movement of the coal outward through said pan, and means to retain said doors with their arms horizontal, substantially as shown and described.

115

3. In a coal or other wagon, the combination with a body having a delivery-aperture in its bottom, of a delivery-pan arranged below said aperture and extending from side to side of said body, means to permit either end 120 of said pan to drop to a limited distance, means to support the other end of the pan, vertically-movable gates carried by said body and adapted each to engage the corresponding end of said pan to raise the same and 125 means to raise and lower said gates, substantially as shown and described.

120

4. In a coal or other wagon, the combination with a body having a delivery-aperture in its bottom, of a delivery-pan arranged below said aperture and extending from side to side of said body, means to permit either end 130 of said pan to drop to a limited distance, vertically-movable gates carried by said body

130

and having each a hook, a bolt at each end of said pan to engage the corresponding hook and means to raise and lower said gate, substantially as shown and described.

5. In a coal or other wagon, the combination with a body having a delivery-aperture in its bottom, of a delivery-pan arranged below said aperture and extending from side to side of said body, doors or plates hinged to said body at each end of said aperture and having slotted arms to engage the corresponding end of said pan, said doors having each an aperture, said pan having at each end a tongue to enter the aperture in the corresponding door and to receive a locking-pin, substantially as shown and described.

10. In a coal or other wagon, the combina-

tion with a body having a delivery-aperture in its bottom, of a delivery-pan arranged below said aperture and extending from side to side of said body, said pan having laterally-projecting pins at each end thereof, swinging arms carried by said body and slotted to engage said pins, hangers secured to the under side of said body and delivery-chutes supported by said hangers and having fingers to engage said pins, substantially as shown and described.

15. This specification signed and witnessed this 3d day of January, A. D. 1896.

GEORGE B. MARX.
